CLAIM

The ornamental design for a combination sharpener having two sharpening components, as shown and described.

DESCRIPTION

FIG. 1 is a perspective view looking downward of the combination sharpener having two sharpening components showing our new design;

FIG. 2 is a front elevational view thereof;

FIG. 3 is a rear elevational view thereof;

FIG. 4 is a top plan view thereof;

FIG. 5 is a bottom plan view thereof showing the two sharpening components of the combination sharpener;

FIG. 6 is a right end elevational view thereof;

FIG. 7 is a left end elevational view thereof;

FIG. 8 is a bottom plan view of FIG. 1 showing the second sharpening component removed from the first sharpening component;

FIG. 9 is a perspective view of FIG. 8;

FIG. 10 is a perspective view of the second sharpening component shown removed from the first sharpening component for completeness of illustration;

FIG. 11 is a front elevational view of FIG. 10;

FIG. 12 is a rear elevational view of FIG. 10;

FIG. 13 is a top plan view of FIG. 10;

FIG. 14 is a bottom plan view of FIG. 10;

FIG. 15 is a right side view of FIG. 10; and,

FIG. 16 is a left side view of FIG. 10.

The broken lines in FIGS. 5, 8, 9 and 14 illustrate portions of the design that form no part of the claim.
